STOP MOTION FOR KNITTING MACHINES

Michael Antonevich, Franklin Township, Somerset County, N. J., assignor to Crawford Manufacturing Company, New Brunswick, N. J., a corporation of New Jersey

Application April 3, 1939, Serial No. 265,823

6 Claims. (Cl. 66—163)

This invention relates to stop motions for knitting machines and others in which textile threads are employed and which must be stopped promptly should the thread break or become abnormally slack or abnormally taut.

The invention more specifically relates to stop motions of the general type disclosed in the prior patent to Alfred Crawford No. 1,992,860, dated February 26, 1935, and assigned to the Crawford Manufacturing Company of New Brunswick, New Jersey, the assignee of the present case.

In devices of the type disclosed in said prior patent there is a series of arms radiating from a central hub casing. In the casing there are two sets of tension springs arranged with one end of each spring of one set attached to a common tensioning spider, with the opposite ends of the springs of the set respectively connected to levers fixed on the inner ends of tubular shafts which are journaled in the radiating arms with their inner ends projecting into the hub casing. The second set of springs has one end of each spring connected to a second common tensioning spider, with the opposite ends of the springs of the set respectively connected to levers which are secured to shafts respectively journaled in the tubular shafts.

The inner shafts are respectively provided with thread-controlled fingers at the outer ends of the radiating arms. The tubular shafts are respectively provided with levers having projections underlying the fingers on the inner shafts. The springs connected to the levers on said shafts, and which with their common regulating spiders are located within the casing, under conditions of abnormal tension in the threads respectively engaged by the fingers, cooperate to resist turning of the shafts by such tensioning of the threads.

It is necessary in the type of device noted to provide equal resistance to the rotations of the shafts on all of the arms in order that the threads engaging the fingers carried by the arms will be fed to the needles of the knitting machine under substantially the same tension, in order that the stitches knitted from the different threads will all be of the same size in the completed fabric.

In order to place all of the thread-controlled fingers under the same degree of resistance to rotation by the respective threads it is necessary to test and regulate each of the springs of each series individually before the springs are placed in the hub casing and connected at their opposite ends to the common tensioners and the

levers on the shafts which carry the fingers, so that, when the common tensioner for either series of springs is operated equal resistance to rotation of the fingers by the threads will be applied thereto.

The individual testing and regulation of the springs, in order to make all springs of each series alike, is a laborious and time-consuming operation and at the best is not entirely satisfactory.

One object of the present invention is to construct a device in a manner to eliminate the necessity for the individual testing and regulation of the several springs of the two series.

Another disadvantage inherent in constructions having an inner shaft journaled within a tubular shaft for relative rotation between the two is that a slight warping or bending of either shaft will cause a binding between the two shafts and a consequent disruption of the rather delicate operation of the finger carried by the one shaft and complementarily acted upon by the other shaft.

Another object of the invention, therefore, is to provide a construction in which the necessity for journaling one shaft within another is eliminated.

The construction and operation of a stop motion device made in accordance with the principles of the present invention will be fully disclosed hereinafter, reference being had to the accompanying drawings, of which:

Fig. 1 is a plan view of a segmental section of the central hub casing with one of a plurality of radiating arms projecting therefrom;

Fig. 2 is an end view of the mechanism of the stop motion device shown in Fig. 1;

Fig. 3 is a longitudinal sectional elevation of the outer end of the arm and mechanism thereon, as taken on the line 3—3, Fig. 1;

Fig. 4 is a front elevation of the outer end of the arm and a longitudinal sectional elevation of the inner end of the arm and the hub casing with the section taken on the line 4—4, Fig. 1;

Fig. 5 is a face view of the switch mechanism illustrated in Fig. 4;

Fig. 6 is a rear elevation of the outer end of the arm and the mechanism carried thereby as shown in Fig. 1;

Fig. 7 is a transverse sectional elevation taken on the line 7—7, Fig. 1;

Fig. 8 is a transverse sectional elevation taken on the line 8—8, Fig. 1; and

Fig. 9 is a detached perspective view of the

elements normally located at the outer end of the arm.

Referring to Figs. 1 and 4, the central hub casing is illustrated at 1, with an arm 2 rigidly connected at its inner end to the hub casing 1 and extending radially from said casing in a substantially horizontal plane.

It will be understood that the device normally comprises a plurality of arms 2, equal in number to the number of threads being fed to the needles of a knitting machine to which the stop motion is attached; and that each arm carries the same mechanism which is shown in connection with the arm illustrated in the drawings.

Journalled at 3, in the wall of the hub casing 1, and at 4, in a bearing bracket 5 secured to the arm 2, is a single shaft 6. Secured to the inner end of the shaft 6, within the casing 1, is a double arm lever 7. The opposite ends 8 and 9 of the lever 7 are disposed at opposite sides of the axis of the shaft 6 and are respectively arranged to engage a movable switch element 10, to rock said element about its pivot 11, into contact with a stationary switch element 12, against the tension of a spring 13, when the shaft 6 is rocked in either clockwise or a counterclockwise direction under circumstances hereinafter noted.

Secured to the outer end of the shaft 6, beyond the bearing 4, is a yarn or thread-engaging finger 15.

The finger 15 is arranged to be rocked in one direction, i. e. in the direction of the arrow *a* (Fig. 2), by a primary torque-applying spring 16, one end of which is connected to a rear or lever portion 11 of the finger 15. The opposite end of the spring 16 is connected to an anchor element 18. The anchor element 18 is adjustably mounted on a bracket 19 carried by and depending from a frame 20 having a base portion secured, by a screw 21, to the outer end of the arm 2. Adjustment of the element 18 toward and away from the shaft 6 regulates the normal primary torque applied to the finger 15 by the spring 16.

The frame 20 is provided with a lug 22 in which is secured a screw stud or post 23. The stud 23 is arranged in laterally spaced parallel relation to and above the axis of the shaft 6. Between the head of the stud 23 and the outer side of the lug 22 is a spacing sleeve 24 on which is rotatably mounted a hub 25 of a complementary torque lever 26.

The lever 26 is provided with a lateral extension 27 which projects under but is normally out of contact with the thread finger 15. The complementary torque lever 26 is adapted to be swung in the direction of the arrow *b* (Fig. 2) by a secondary or complementary torque-applying spring 28.

One end 29 of the spring 28 is anchored in an opening 30 formed in the lever 26. The opposite end 31 of the spiral spring 28 is anchored in an opening 32 formed in a complementary torque regulating or adjusting element 33. The torque-regulating element 33 is in the form of a knurled knob or wheel rotatably mounted on the sleeve 24, between the head of the screw stud 23 and the outer end of the hub 25 of the lever 26.

Movement of the complementary torque-applying lever 26 in the direction of the arrow *b* (Fig. 2) is limited by a stop 34 which is in the form of a flat spring secured to the frame structure 20 by the screw 35 and thereby the lateral projection 27 of the lever 26 is prevented from moving upwardly a sufficient distance to en-

gage the finger 15 when the latter is supporting a thread under normal torque of the spring 16 acting against a counteracting normal torque applied in the opposite direction by normal tension on the thread engaged by the finger 15.

The peripheral edge or face 36 of the torque-regulating element 33 is serrated, as shown in Fig. 9, for engagement by a detent 37 which is in the form of a flat spring secured to the base element 20 by the screw 21. A guide screw 38 mounted in the structure 20 passes through the spring detent 37 to prevent lateral movement of the detent while permitting vertical movement of the outer end of the detent, by a depressed rib 39 of said detent riding the serrations 36 of the torque regulator 33.

Under normal operation of the device, the tension of the spring 16 applies a normal torque to the shaft 6 and finger 15 which is counteracted by a normal torque produced by normal tension of the knitting thread passing over the finger 15. Thus the finger 15 assumes the normal broken line position of Fig. 2. Under these conditions the ends 8 and 9 of the switch-operating lever 7 on the inner end of the shaft 6 within the casing 1 are in a neutral position, with the movable switch element 10 out of contact with the relatively stationary switch element 12.

If the thread passing over the finger 15 should become subnormally slack or break, the finger 15, under normal torque applied by the primary spring 16, will swing upwardly beyond the normally broken line position (Fig. 2) and rock the shaft 6 accordingly.

Rocking of the shaft 6, as noted, will cause the lower end 9 of the lever 7 to move the switch element 10 into contact with the switch element 12 and thereby close an electrical circuit by which prompt stopping of the machine is effected as and by mechanism shown in the prior patent hereinbefore referred to.

If the thread passing over the finger 15 should become abnormally taut, the finger 15 will be moved downwardly in the direction of the arrow *c* (Fig. 2) from the broken line position to the full line position in said figure and cause the lower side of the finger 15 to make contact with the lateral projection 27 of the complementary lever 26. As the tightening of the thread over the finger 15 increases the finger 15 and the complementary lever 26 engaged thereby will move downwardly in unison, from the full line position shown in Fig. 2, against the combined torque or force exerted in the opposite direction by the primary spring 16 and the secondary spring 28. This rocks the shaft 6 in the opposite direction to that above noted and causes the upper end 8 of the lever 7 to contact with the switch element 10, rocking said element 10 about its pivot 11 into contact with the switch element 12, whereby the machine will be brought to a stop in the same manner as above noted.

From the above, it will be clear that the regulating elements 18 may be independently adjusted toward and away from the shafts 6 for independently regulating the tensions of the primary springs 16 and correspondingly regulating the normal torque applied to each thread-engaging finger 15; and that this independent regulation of the primary normal torques on the fingers 15 is readily accomplished by independent mechanisms disposed externally of the hub casing 1.

It will also be clear that a correspondingly independent regulation of the complementary torques applied to the fingers 15 can be readily

accomplished through means located outside the casing 1 by merely turning the complementary torque-regulating knobs or wheels 33.

In addition to eliminating the necessity for accurately equalizing all the springs of the device disclosed in the above noted prior patent before assembling the device, as noted above, the arrangement of parts on which the present case is predicated makes it possible to regulate and equalize the tensions on the various threads being fed to the knitting machine and drawn from different cones or other packages respectively wherein the thread or threads from one or more cones have been wound differently on the respective packages which alone or with other circumstances or conditions causes the threads to pull harder or easier, as the case may be, from the package as the threads are being drawn into the needles of the knitting machine.

I claim:

1. In a stop motion device comprising a central casing and a plurality of arms radiating therefrom, a single operating shaft journaled in each arm with one end projecting into said casing, a thread-engaging finger secured to each shaft adjacent the outer end of each arm, resilient means individual to each finger and its shaft for exerting a predetermined torque thereon constantly in one direction in opposition to a counteracting torque exerted on the finger by the tension of the thread engaging the finger, normally ineffective means for applying additional torque to said shaft, means on the inner end of the shaft for effecting operation of the stop motion upon unbalancing of said counteracting torques and a resultant turning of the shaft, and means carried by each arm externally of the casing and individual to each of said resilient means and to each of said additional torque applying means for independently regulating the torque applied thereby to its corresponding shaft and finger respectively.

2. In a stop motion device comprising a central casing and a plurality of arms radiating therefrom, a single operating shaft journaled in each arm with one end projecting into said casing, a thread-engaging finger secured to each shaft adjacent the outer end of each arm, primary resilient means individual to each finger and its shaft for exerting a predetermined torque thereon in one direction in opposition to a counteracting torque exerted on the finger by the tension of the thread engaging the finger, means on the inner end of the shaft for effecting operation of the stop motion upon unbalancing of said counteracting torques and a resultant turning of the shaft, means carried by each arm externally of the casing and individual to each of said primary resilient means for independently regulating the torque applied thereby to its corresponding shaft and finger, a normally ineffective secondary resilient means for applying a complementary torque to said finger and its shaft in the same direction as said primary resilient means upon abnormal overbalancing of the torque of said primary resilient means by abnormal tension developing in said thread, and means individual to each secondary resilient means carried by each arm externally of said casing for independently regulating the complementary torque applied thereby.

3. In a device of the kind described comprising an outwardly projecting arm, a shaft journaled on the arm, a thread-engaging finger secured to the shaft adjacent the outer end of the arm, a

lever secured to said shaft, an element adjustably mounted on the arm for movement toward and away from said shaft, a primary spring having one end anchored to said lever and the opposite end anchored to said adjustable element for regulating the torque applied to said shaft and finger by said spring in opposition to a counteracting torque applied to the finger by a thread engaged thereby, a second lever pivotally mounted on said arm with an outer end normally lying in the path of movement of said finger, means normally holding said second lever from contacting said finger, a second spring having one end anchored to said second lever and applying a predetermined torque on said second lever in the same direction as the primary torque is applied to said finger by said primary spring, and means adjustably mounted on said arm and to which the second end of said second spring is anchored for regulating the torque applied thereby to said second lever, said finger under abnormal overbalancing of the torque applied thereto by said first spring moving into contact with said second lever and receiving a complementary concurrent torque applied thereto by said second spring for opposing abnormal tension developing in the thread engaged by said finger.

4. The combination of an outwardly projecting arm, a shaft journaled on said arm, a stud secured in said arm and extending parallel to said shaft, a thread-engaging finger secured to said shaft, means for applying a primary predetermined torque to said shaft for opposing a normal counteracting torque applied to said finger by a thread engaged thereby, a lever pivoted on said stud with one end in the path of movement of and normally out of contact with said finger, a wheel rotatably mounted on said stud, a spring encircling said stud with one end anchored to said lever and its opposite end anchored to said wheel, and means for securing said wheel against rotation by said spring for maintaining a predetermined torque on said lever through the spring interposed between said wheel and said lever.

5. The combination of an outwardly projecting arm, a thread-engaging finger pivotally mounted on said arm adjacent the outer end thereof, a stud secured in said arm, an adjusting element rotatably mounted on said stud, a spring encircling said stud with one end anchored to said adjusting element and the opposite end arranged to apply a torque to said finger in opposition to a counteracting torque applied to the finger by tension of a thread engaged by the finger, and a detent for maintaining said torque of said spring.

6. The combination of a casing, an arm projecting outwardly from said casing, a shaft journaled in said arm with one end in the casing, a thread-engaging finger secured to the shaft externally of the casing, a double arm lever secured to the shaft within the casing, resilient means applying torque to the shaft in one direction in opposition to a counteracting torque applied to the shaft by tension on the thread engaged by said finger, a stationary switch element in said casing, a movable switch element pivotally mounted in the casing adjacent said shaft and said double arm lever thereon and movable into contact with said stationary switch element by engagement with either of said lever arms by unbalancing of said torques and consequential rocking of the shaft.

MICHAEL ANTONEVICH.
